CLAIM

The ornamental design for an oral irrigator, as shown and described.

DESCRIPTION

FIG. 1 is a front isometric view of an oral irrigator with a toothbrush and an oral irrigator handle with a nozzle tip shown in dashed lines for environment.

FIG. 2 is a front isometric view of the oral irrigator of FIG. 1.

FIG. 3 is a front elevation view of the oral irrigator of FIG. 1.

FIG. 4 is a rear elevation view of the oral irrigator of FIG. 1.

FIG. 5 is a right side elevation view of the oral irrigator of FIG. 1.

FIG. 6 is a left side elevation view of the oral irrigator of FIG. 1.

FIG. 7 is a top plan view of the oral irrigator of FIG. 1; and, FIG. 8 is a bottom plan view of the oral irrigator FIG. 1. The broken line showing of the toothbrush and oral irrigator handle with nozzle tip in FIG. 1 illustrates environment and forms no part of the claimed design. All other broken lines illustrate portions of the oral irrigator that form no part of the claimed design.
